(57) **CLAIM**

The ornamental design for a laminated baking tray, as shown and described.

DESCRIPTION

FIG. 1 shows a perspective view of the laminated baking tray of the present invention.

FIG. 2 shows a side view of the laminated baking tray of the present invention. The other side of the laminated baking tray is identical to the side shown in FIG. 2, and, thus, no second side view is presented.

FIG. 3 shows an end view of the laminated baking tray of the present invention. The other end of the laminated baking tray is identical to the end shown in FIG. 3, and, thus, no second end view is presented; and,

FIG. 4 shows a top view of the laminated baking tray of the present invention.

The bottom of the laminated baking tray of the present invention is plain and unornamental, and, thus, no bottom view is presented.
